Design No. 293. —

James Wager

David Pratt

Volney Richmond

Design for Stoves

Patented June 18, 1850.

Ms. 193

Wager, Pratt and Richmond of Troy N. Y.
Letters Patent No. 293. Dated June 18, 1850.

The Schedule referred to in these Letters Patent and making part of the same.

To all to whom these presents shall come:

Be it known that we James Wager
David Pratt and Volney Richmond under the firm name of Wager, Pratt & Co. all of Troy and
County of Rensselaer in the State of New York have constructed a new design for Cooking Stoves and
that the following is a full clear and exact description of the character which distinguishes it from
all other things before known.

Our design consists of certain ornamental plates of pec-
uliar configuration to suit the purposes of the stove to which it is adapted.

The general figure is oblong like most modern stoves
for cooking purposes - a plain O. G. and oval moulding surrounds the top of the stove - the doors -
which are three in number on the side shown in the drawing have a star ornament in the centre
with beaded rays reflecting in every direction from the same to the outer edge which is surround-
ed by a combination of bead and cove mouldings and the front upper corner of the oven door
is cut off angularly slightly curved as is shown in the drawing - the front doors open each way
from the centre and have the same ornaments in the centre and are surrounded by the same
mouldings as the side doors before described - The bottom of the stove has a plain cove moulding
projecting from the body of the stove with an addition of a small quarter bead moulding around
the extreme edge and clearly shown in the perspective view.

Having thus fully described our improvement what
we claim therein as new and for which we desire to secure Letters Patent is the above described

Des. 293

29

ornamental design and configuration of the plates as described and represented.

Wilmfors.
